(57) **CLAIM**

The ornamental design for a battery pack, as shown and described.

DESCRIPTION

FIG. 1 is a perspective view of the battery pack showing our new design;

FIG. 2 is a side view of the battery pack shown in FIG. 1;

FIG. 3 is a rear view of the battery pack shown in FIG. 1;

FIG. 4 is a front view of the battery pack shown in FIG. 1;

FIG. 5 is a bottom view of the battery pack shown in FIG. 1; and,

FIG. 6 is a top view of the battery pack shown in FIG. 1.

The broken line representations in FIGS. 1 and 5-6 are for illustrative purposes only and form no part of the claimed design. The left side of the battery pack is a mirror image of the right side.
